UNITED STATES PATENT OFFICE.

FREDERICK M. TURCK AND BRUCE CLARK WHITE, OF NEW YORK, N. Y.

SHEET-DELIVERING DEVICE FOR PRINTING-PRESSES.

1,306,088.

Specification of Letters Patent. Patented June 10, 1919.

Application filed August 29, 1917. Serial No. 188,765.

To all whom it may concern:

Be it known that we, FREDERICK M. TURCK and BRUCE C. WHITE, citizens of the United States, and residents of New York, in the county of New York and State of New York, have invented certain new and useful Improvements in Sheet-Delivering Devices for Printing-Presses, of which the following is a specification.

10 This invention relates to improvements in printing presses in which sheets are fed to a sheet carrier, printed upon and finally released and delivered, and particularly to such a type of printing press as is shown and described in Patent No. 1,146,039, dated July 13th, 1915, issued to Frederick M. Turck, and also shown and described in several of our applications for Letters Patent of even date herewith.

20 The object of our invention is to provide operative means for releasing only such sheets as have received their final printing, and directing such released sheets away from the press.

25 Another object of our invention is to render the sheet releasing and sheet delivery mechanism inoperative upon unprinted or partially printed sheets as they pass the point of delivery.

30 The invention also includes certain details of construction hereinafter set forth.

In describing the invention in detail reference is had to the accompanying drawings forming a part of this specification, where- 35 in like characters of reference are used to designate corresponding parts throughout the several views and in which:

Figure 1 is a general side elevation of a multi-color press to which this sheet delivery may be adapted. Fig. 2 is an enlarged side elevation of the delivery mechanism. Fig. 3 is a transverse section of same on line 1, 1 of Fig. 5 showing the sheet grippers opened while the directing tapes are still in their normal or undeflected position. Fig. 4 is similar to Fig. 3 except that the grip opening device or tumbler has retired to its normal position while the sheet deflecting tapes are shown in a position to

direct the sheet onto the off-bearing tapes. 50 Fig. 5 is an end elevation of a part of the delivery device. Fig. 6 is a plan view of a part of the delivery device. Fig. 7 is a detail side elevation of the gripper opening mechanism showing the parts from the opposite side of the press from that of Fig. 2. Fig. 8 is a section of the same upon line 2, 2 of Fig. 7. Fig. 9 is a section through the tape-tension device on line 3, 3 of Fig. 10. Fig. 10 is a sectional elevation of the same 60 on line 4, 4 of Fig. 9. Fig. 11, is a horizontal section of the tape-tension adjustment on line 5, 5 of Fig. 2.

Referring to Fig. 1, numeral 1 designates the bed-plate of the press, upon which are 65 mounted the frames 2 and 3. In the latter are journaled the two printing couples composed of the form or plate cylinders 4 and 5, and the impression cylinders 6 and 7.

A power pulley 8 drives the cylinders 70 through gearing, more fully shown and described in another of our applications, filed Aug. 29, 1917, Serial Number 188,764, to which reference is also made for more detailed descriptions of the sheet-feeding de- 75 vice sheet-carrier and sheet-grippers.

Means are provided at 9 and 10 for inking the surface of the printing-plates upon the cylinders 4 and 5 such means comprising the usual fountains 11, 12, 13 and 14, form 80 rollers 15 and appropriate distributing means.

For advancing the sheets to be printed upon, a sheet-carrier is provided, composed of oppositely-disposed annular toothed carrier rings 16, rigidly connected together by cross-braces or sheet-carriers 17. The carrier rings are geared to the cylinders 6 and 7 by gear rings 18.

In the machine herein shown a sheet is 90 fed to one of the sheet-carriers 17 for each revolution of the printing cylinders. Each cylinder has three divisions, each of which registers with a division or cross-brace 17 of the sheet-carrier of which there are 95 seven. Every third cross-brace or sheet-carrier 17 delivers a finished sheet at each revolution of the cylinder 6 and later re-

ceives a fresh sheet. This we accomplish preferably as follows:

Upon one end of cylinder 6 is formed a cam track 19 which is concentric for the 5 larger portion of its periphery. For the remaining portion the track is extended radially by a gradual curve 20. This extended portion of the track 21 extends in a concentric curve for a short distance, then recedes 10 to the shorter radius at 22. See Fig. 4. Arch shaped frames 23 provide bearings for each end of the rock shaft 24 which extends across the machine. To the shaft 24 is keyed a cam arm 25. Clamped into the outer end 15 of the latter by the bolt 26 is a roller-pin 27, upon which is journaled the cam-roller 28 which rides upon the cam track 19, 20, 21 and 22. To the shaft 24 are keyed two arms 29 the upper ends of which form journals 20 30 for a cross-shaft 31 upon which are mounted tape pulleys 32. Tape pulleys 33 are secured to the driving-shaft 34 which is mounted to run freely in bearings 35 in the arch-frames 23. See Figs. 3, 4 and 6. A 25 gear-wheel 36 is keyed to the driving shaft 34, in position to mesh with one of the internally toothed gear rings 16, whereby the tape pulleys 33 will be driven in the proper direction and at a peripheral speed corresponding 30 with the linear printing speed of the sheet. Tapes 37 are trained about the tape-pulleys 32 and 33 and about the two tension rollers 38 as shown in Fig. 3. The rollers 38 are each provided with a shaft 39, 35 the projecting ends of which journal in bearings 40 formed in the heads 41. The latter are secured and keyed to a tension-roller shaft 42 which is journaled to rotate freely in bearings 43 in the arch-frames 23. Rods 40 44 are pivotally connected, one to each of the heads 41, by means of pins 45, rigidly secured thereto by nuts 46. Each of the rods 44 is free to slide axially in the adjusting screw 47 which has screw-thread engagement 45 with the puppet 48. The latter is provided with a round shank 49 which is fitted to turn freely in a hole in each arch-frame 23 and is retained therein by the washer 50 and screw 51. A compression spring 52 encircles 50 each rod 44 and thrusts against the head 53 thereof at one end and at its opposite end it thrusts against the end of the adjusting screw 47. By turning these screws the tension of the springs may be 55 altered as desired. The jam-nuts 54 on the screws 47 provide means for locking the screws in their adjusted positions. The oscillation of the puppets 48 is necessitated for the reason that the pins 45 describe an arc 60 in moving from the position shown in Fig. 3 to that shown in Fig. 4. The action of the springs is such as to tend to thrust the heads 41 and rollers 38 into the position shown in Fig. 3 and draw the tapes 37 taut.

If the cam roller 28 be lifted by cam 20 and 65 with it the arm 25, arms 29, shaft 31 and pulleys 32 these parts will assume the position shown in Fig. 4, also shown in Fig. 6 in dotted lines. The distance between tape-pulleys 32 and 33 is thereby increased but 70 such increase is provided for by the turning of the rollers 38 and their heads 41 from the position of Fig. 3 to that of Fig. 4, against the thrust of springs 52 which are thereby compressed but which insure a tension 75 on the tapes in whatever position the tape-pulleys 32 may be moved. When the latter are in the position shown in Fig. 3 the tapes 37 will form a support for the sheet as it is carried forward and downward toward 80 the first printing couple 4 and 6. When the pulleys 32 and tapes 37 are in the position shown in Fig. 4 the tapes still form a support for the sheet which being released from the grippers in sheet carriers 17 will be delivered upon the off-bearing tapes 55. These latter are trained about pulleys 56, mounted upon shaft 57 for which bearings are provided in the arch-frames 23. The pulleys 56 are preferably so spaced laterally that the pulleys 32 will be between them to form a practically continuous tape support for the sheet when delivering. This is important for the reason that the sheet is uncontrolled from the instant the grippers 58 95 in the sheet-carrier 17 release it except for the tapes upon which it rests. These latter, running at a fixed speed at practically a straight line tangent to the normal sheet path form a delivery device in which the 100 sheet is unaffected by frictional resistance or static electricity in its course away from the press.

The grippers 58 are secured to the gripper-shaft 59. This shaft extends through the 105 gear-rings 16 in which bearing sleeves are provided for it. These sleeves extend through the end walls of the sheet-carriers 17 forming dowels for accurately locating the sheet-carriers 17 between the rings 16. 110 Screws further secure the rings to the sheet carriers. See Figs. 7 and 8. Keyed to each of the projecting ends of each of the gripper-shafts 59 is a tumbler arm 60. Teeth 61 are formed across the end of this arm as a short 115 sector of a spur gear. A short sector of a spur pinion 62 meshes into the teeth of arm 60. The pinion 62 is mounted to turn freely upon stud 63. The pinion 62 is extended at a point opposite its teeth to form an arm, 120 through which passes a pin 64. This pin also passes through the end of a spring rod 65, about which is coiled the compression tumbler-spring 66. This spring thrusts 125 against the puppet 67 in a manner to thrust the arms into the extreme angular position after having been moved by the tumbler-pin to the position shown in Fig. 7. The tum-

bler arm 60 is widened out by the inner projection or hump 68 and the outer projection or hump 69 of such form that when the parts are in the position shown in Fig. 7 the 5 inner hump 68 has come into contact with the roller 71 upon the pin 70 which latter is firmly secured by the nut 72 in the upper end of the arm 73 of the tumbler-lever 74. The lower arm 75, the hub 76 and the upper 10 arm 73 of the lever 74 are preferably made integral, the hub 76 is bored to turn freely upon the stud 77 which latter is secured firmly in the arch frame 23 by the nut 78 and washer 79. See Fig. 8. The arm 74 is 15 retained upon the stud 77 by the nut 80 and washer 81. At the lower end of the branch 75 of the lever 74 is a roller pin 82, firmly clamped to the arm 75 by the clamp screw 83. A cam roller 84 similar to cam-roller 20 28 is arranged to roll upon the cam track 19, 20, 21 and 22 and be lifted thereby for a short interval at every rotation of the cylinder 6 whereby the roller 71 will act to open the grippers of every third sheet. The 25 cam-roller 84 as will be seen from Figs. 2, 3 and 4 which opens the grippers, acts in advance of cam-roller 28 which changes the direction of the tapes 37. The cam 20, 21, 22 is located upon the cylinder 6 in a position 30 to deliver a finished sheet from that division of the sheet-carrier corresponding with blank section of the cylinder 6 and its corresponding cylinder 4. The grippers 59 opened by the arm 74 will remain open until 35 a fresh sheet has been fed to them when they are closed as described in another application made by us of even date herewith.

The off-bearing tapes 55 are preferably driven at the same lineal speed as the tapes 40 37 and by mechanism not shown but preferably located at the outer end of said tapes. The particular advantages of this form of delivery are that it is adapted to a printing-press in which only certain sheets are to be 45 delivered while the intermediate sheets may continue in their course to the printing units. This adapts it to a position between the feed and the first printing. This is the only practical arrangement of printing couples, 50 feed and delivery. If the order is reversed and the delivery occurs between the final printing and the feed, a tangent delivery upon tapes must be abandoned and for it must be substituted some form of delivery, 55 in which the direction of the delivering sheet must be reversed about a drum or roller to get the sheet away. This reversing roller or other device contacts directly with freshly printed surface of the sheet and has the further disadvantage of turning the sheet up 60 side down. A still further disadvantage of such an alternative arrangement lies in the fact that both the feed and delivery would be located at the same end of the press, one

above the other, which is inconvenient for 65 both. Another important advantage gained by the particular construction shown lies in the fact that the sheet is supported while delivering entirely by tapes running in a horizontal direction at a tangent to their 70 curved path and at a constant speed thus spacing them accurately on the off-bearing belt. This simplifies their piling, interleaving or introduction into another press for subsequent operations. 75

While we have shown and described the preferred embodiment of the invention, it will be obvious that various changes may be made as regards its form, detail construction and general arrangement without departing 80 from the principle and scope of the invention.

What we claim as our invention and desire to secure by Letters Patent, is:

1. In a sheet delivery for a printing press 85 a sheet carrier; grippers thereon for gripping the advance edge of a sheet; endless tapes for sustaining the remaining portion of said sheet; driving pulleys for said tapes at one end and movable pulleys at the other 90 end and means for moving the latter pulleys whereby a sheet upon said tapes will be directed to the printing couple of said press or will be diverted to an off-bearing device.

2. In a sheet delivery, for a printing press, 95 an arm for opening the grippers of a sheet carrier to release a sheet therefrom; an arm for shifting the position of the tapes supporting the said sheet when the latter is released; and a cam engaging first the grip-releasing arm, then the tape shifting arm; and means for operating the tapes. 100

3. In a sheet delivery for a printing press, 105 a sheet-carrier arranged to carry a sheet in a circular path; a sheet-delivering device arranged interiorly of said path; a sheet-delivering device arranged exteriorly of said path; means for releasing the sheet from said carrier; and means for transferring the sheet from said inner delivery to said outer 110 delivery.

4. In a sheet delivery for a printing press, 115 a sheet-carrier arranged to carry a sheet in a circular path; a sheet-delivering device arranged to support the sheet interiorly of said path at a speed corresponding therewith; a sheet-delivering device arranged to support the sheet exteriorly of said path at a speed corresponding therewith; means for releasing the sheet from said carrier; and means 120 for transferring the sheet from said inner delivery to said outer delivery.

5. In a sheet delivery for a printing press, 125 a sheet-carrier arranged to carry a sheet in a circular path; a sheet-delivering device arranged interiorly of said path; a sheet-delivering device arranged exteriorly of said path; one of said deliveries being extensible

toward the other to present a substantially uninterrupted delivery surface; means for releasing the sheet from said carrier; and means for operating said extensible delivery 5 and transferring the sheet from said inner delivery to said outer delivery.

6. In a sheet delivery for a printing press, a sheet-carrier arranged to carry a plurality of sheets in a circular path; a sheet-delivering device arranged to support the sheets interiorly of said path at a speed corresponding therewith; a sheet-delivering device arranged to support the sheets exteriorly of said path at a speed corresponding therewith; the inner of said deliveries being extensible toward the outer one to provide a substantially uninterrupted delivery surface; means for releasing a sheet from said carrier; means for extending said inner delivery and transferring the released sheet to said outer delivery; and means for returning said inner delivery for the reception of the succeeding sheet.

7. In a printing press, a sheet-carrier having grippers arranged to engage the leading edge of a sheet; a sheet support comprising a series of tapes alined in the path of said carrier to receive the body of said sheet; means for driving said carrier and supporting tapes at a common speed; means for releasing the grippers of said carrier; and means for deflecting the path of said supporting tapes for the delivery of the sheet.

8. In a printing press, a sheet-carrier having a plurality of carrier-bars provided with grippers arranged to engage the leading edges of a plurality of sheets; a sheet support comprising a series of tapes alined in the path of said carrier to receive the body of the sheets; means for driving said carrier and supporting tapes at a common speed; means for releasing the grippers of a carrier-bar and deflecting the path of the supporting tapes for the delivery of a sheet; and means for returning the supporting tapes to their normal path for the reception of a succeeding sheet.

9. In a printing press, a sheet-carrier having grippers engaging the leading edge of a sheet; a sheet support comprising a series of tapes alined in the path of said carrier to receive the body of the sheet; a sheet delivering device arranged exteriorly of the path of said carrier; means for driving said carrier and supporting tapes at a common speed; means for releasing the grippers of said carrier; and means for deflecting the path of said supporting tapes for the transfer of the sheet to said delivery device.

60 10. In a printing press, a sheet-carrier having a plurality of carrier-bars provided with grippers arranged to engage the leading edges of a plurality of sheets; a sheet support comprising a series of tapes alined

in the path of said carrier to receive the body of the sheets; a sheet delivery device arranged exteriorly of the path of said carrier; means for driving said carrier and supporting tapes at a common speed; means for releasing the grippers of one of said carrier bars; means for deflecting the path of said supporting tapes and transferring the released sheet to said delivery device; and means for returning said supporting tapes to their normal path for the reception of a sheet of a succeeding carrier-bar.

11. In a printing press, a printing couple; a sheet-carrier having grippers engaging the leading edge of a sheet and feeding the same to said couple; a sheet support comprising a series of tapes alined in the path of said carrier to receive the body of the sheet; and means for driving said carrier and supporting tapes at a speed common with the printing speed of said couple.

12. In a printing press, a printing couple; a sheet-carrier having grippers engaging the leading edge of a sheet and feeding the same to said couple; a sheet support comprising a series of tapes alined in the path of said carrier to receive the body of the sheet; means for driving said carrier and supporting tapes at a speed common with the printing speed of said couple; and means for deflecting the path of said supporting tapes for the delivery of the sheet.

13. In a printing press, a printing couple; a sheet-carrier having a plurality of carrier-bars provided with grippers arranged to engage the leading edges of a plurality of sheets and feed the same to said couple; a sheet support comprising a series of tapes alined in the path of said carrier to receive the body of the sheets; means for driving said carrier and supporting tapes at a speed common with the printing speed of said couple; means for releasing the grippers of a carrier-bar; means for deflecting the path of the supporting tapes for delivering the released sheet; and means for returning the supporting tapes to their normal path for the reception of the sheet of a succeeding carrier-bar.

14. In a printing press, a printing couple; a sheet-carrier having grippers engaging the leading edge of a sheet and feeding the same to said couple; a sheet support comprising a series of tapes alined in the path of said carrier to receive the body of the sheet; a sheet delivery device arranged exteriorly of the path of said carrier; means for driving said carrier and supporting tapes at a speed common with the printing speed of said couple; means for releasing the grippers of said carrier; and means for deflecting the path of said supporting tapes for the transfer of the sheet to said delivery device.

15. In a printing press, a printing couple;

- a sheet-carrier having a plurality of carrier-bars provided with grippers arranged to engage the leading edges of a plurality of sheets and feed the same to said couple; a
5 sheet support comprising a series of tapes aligned in the path of said carrier to receive the body of the sheets; a sheet delivery device arranged exteriorly of the path of said carrier; means for driving said carrier and
10 supporting tapes at a speed common with the printing speed of said couple; means for releasing the grippers of one of said carrier-
bars; means for deflecting the path of the supporting tapes for transferring the released sheet to said delivery device; and 15
means for returning the supporting tapes to their normal path for the reception of a sheet engaged by a succeeding carrier-bar.

Signed at New York in the county of New York and State of New York this 25th day 20
of August A. D. 1917.
